CLAIM

The ornamental design for a chicken waterer, as shown and described.

DESCRIPTION

FIG. 1 is a top-front-left side perspective view of a chicken waterer;

FIG. 2 is a front view of the chicken waterer of FIG. 1;

FIG. 3 is a back view of the chicken waterer of FIG. 1;

FIG. 4 is a left side view of the chicken waterer of FIG. 1;

FIG. 5 is a right side view of the chicken waterer of FIG. 1;

FIG. 6 is a top view of the chicken waterer of FIG. 1; and,

FIG. 7 is a bottom view of the chicken waterer of FIG. 1.

The broken lines illustrate portions of the chicken waterer

that form no part of the claimed design.

1 Claim, 7 Drawing Sheets
